UNITED STATES PATENT OFFICE.

CLINTON C. MURPHY, OF CHICAGO, ILLINOIS, ASSIGNEE TO P. H. MURPHY COMPANY,
OF PARNASSUS, PENNSYLVANIA, A CORPORATION OF PENNSYLVANIA.

CAR-ROOF.

1,221,892.

Specification of Letters Patent. Patented Apr. 10, 1917.

Application filed July 12, 1915. Serial No. 39,252.

To all whom it may concern:

Be it known that I, CLINTON C. MURPHY, a citizen of the United States, and a resident of the city of Chicago, in the county of Cook and State of Illinois, have invented a new and useful Improvement in Car-Roofs, of which the following is a specification.

This invention relates to flexible outside metal roofs for freight cars of the type shown in my Patent No. 1,133,493, dated March 30, 1915, and particularly to the ridge construction of such roofs.

The objects of the invention are to provide a secure fastening means for the roof sheets at the ridge which will prevent the roof sheets from shifting bodily on the roof sheathing boards but which will permit them to accommodate themselves to distortions of the car frame in service, and to prevent water from entering the car at the ridge. Further objects of the invention are to provide for the easy assembling of the roof on the car, and to facilitate the removal and replacement of worn or damaged roof sheets.

Generally stated, the invention consists in the shape and arrangement of the ridge flanges of the roof sheets and ridge seam covers; and in the provision of a ridge flashing strip extending across the ridge portion of the car for its full length, in which strip are the bosses upon which the roof sheets are pivoted.

Further objects and details of the invention appear in connection with the following description of the roof shown in the accompanying drawings; and what the invention consists in is more particularly defined in the appended claims.

In the drawings, wherein the same reference characters are used as in my Patent No. 1,133,493 to designate similar parts in the several views,

Figure 1 is a plan view of a portion of a car roof embodying the invention;

Fig. 2 is a transverse cross-section of the eaves portion of the roof shown in Fig. 1 on the line 2-2 in Fig. 1, drawn to a larger scale;

Fig. 3 is a longitudinal cross-section of the roof transversely of a side seam between two roof sheets, on the line 3-3 of Fig. 1, drawn to the same scale as Fig. 2; and

Figs. 4 and 5 are transverse cross-sections

through the ridge on the lines 4-4 and 5-5, respectively, in Fig. 1, drawn to the same scale as Fig. 2.

The roof boards 11 are preferably tongued and grooved, and are arranged crosswise of the car, being supported at their eaves ends by the side plate 12 and at their ridge ends by the ridge pole 13. Any suitable car-lines may be used for connecting the side plates to each other and for supporting the ridge pole. Purlins may be arranged across the car-lines parallel to the ridge pole and side plates as additional supports for the roof boards, if desired.

The roof sheets 15 extend from ridge to eaves and are arranged side by side crosswise of the car on the roof sheathing boards in two rows, one row on each side of the ridge. The side edges of the roof sheets in each row are spaced apart, and the ridge ends of the roof sheets of one row are opposite the ridge ends of the roof sheets of the other row with a narrow space between them. The sides and ridge end of each roof sheet are formed with marginal walls or flanges 16, the upper edges of which are turned in and bent down toward the roof sheet, forming sloping tops or inner edges 17 around three sides of the roof sheet.

Ridge seam covers 18 of inverted channel shape straddle the ridge end flanges of the pairs of oppositely disposed roof sheets. The lower edges of the side walls of the ridge seam covers terminate in inturned rebent flanges 19 which are bent up at about the same inclination as the sloping inner edges 17 of the roof sheet flanges. The inner edges of the flanges 19 hook under the inner edges 17 of the roof sheet flanges.

The slope and widths of the flanges 19 and inner edges 17 are such that their extremities lie at about the same distance above the roof sheets, so that the ridge seam covers can be snapped down over the roof sheet flanges and the inner edges of the seam cover flanges 19 will spring under the inner edges of the roof sheet flanges 17, as shown in Fig. 5. A ridge strip 60 is arranged lengthwise of the car over the ridge ends of the roof sheathing boards. This ridge strip may be made in convenient lengths and lapped at the ends to provide a continuous flashing from end to end of the car. The ridge strip is formed with a series of bosses 61 arranged

in pairs, the bosses of each pair being on op-

posite sides of the ridge and positioned on the middle lines of the pairs of oppositely disposed roof sheets.

Battens 22 are arranged between the side flanges of the spaced roof sheets, the width of the battens being slightly less than the width of the spaces between adjacent roof sheets. These battens may be nailed or otherwise secured to the roof sheathing, or they 5 may be left loose thereon and secured by the same means which secures the roof sheets and side seam covers 23 which straddle them. The side seam covers are inverted channel shape, with their side walls 24 hooked under 10 the inner edges 17 of the side flanges of the roof sheets, as shown in Fig. 3. The ridge ends of the side seam covers have upturned flanges 26 across their top walls and the eaves ends have projecting tops 27 which are 15 adapted to be bent down over the eaves of the car to cover the ends of the battens and spaces between their side walls.

The eaves ends of the roof sheets and side seam covers are loosely held down upon 20 the substructure by means of angle flashing strips 28, and angle clips 29. (See Figs. 1 and 2.) The angle flashing strips 28 are arranged lengthwise of the car along the eaves below the ends of the roof sheets, and passing underneath the battens and side seam covers. The inner margins 30 of the flashing strips are folded back over the intermediate portions, and the eaves ends 31 of the roof sheets are turned under and hooked 25 into the turned over inner margins of the flashing strips to form a flexible joint. The outer margins of the flashing strips are bent down over the side of the car, and are fastened thereto. The angle clips 29 are outside of the flashing strips, and are bolted to 30 the side of the car below the eaves. The angle clips are spaced away from the ends of the roof sheets and side seam covers and have bent portions projecting over the eaves 35 and overlying the roof sheets or side seam covers. The angle clips prevent the roof sheets and side seam covers from lifting off the substructure, but do not clamp them rigidly in fixed position. The roof sheets are 40 provided with bosses 35 at the middle points of their ridge ends inside of the ridge flanges, and these bosses 35 register with the bosses 61 of the ridge strip and position the roof sheets at their ridge ends. Running board 45 saddles 36 are arranged across the ridge on the middle lines of the sheets, with their under sides shaped to conform to the ridge peak of the roof and provided at their ends with recesses 37 for the roof sheet bosses. The running board saddles 36 straddle the 50 ridge seam covers and are fastened to the substructure by vertical bolts 38, which pass through holes in the seam covers and ridge strips. The seam covers and ridge strips are

flanged up around the holes for the running board saddle bolts 38 to keep water from following the bolts into the car. The recesses in the running board saddles for the roof sheet bosses and the grooves for the 55 ridge seam covers, are wider than the parts projecting into them in order not to bind the roof sheets laterally.

The ridge corners of the roof sheets, and the ends of the ridge seam covers and side 60 seam covers, are covered by corner caps 39. The corner caps are inverted pan shape, with openings in their end walls to receive the ridge seam covers, and openings in their side walls to receive the battens and side 65 seam covers. The corner caps have center holes which are threaded to fit vertical bolts 42 which secure them to the substructure.

Running board saddles 44 are arranged 70 over the side seam covers, resting on them and being supported by the battens. The running board saddles 44 are recessed for the corner caps, and the securing bolts 42 for the corner caps go through the running board saddles and hold them down. Running boards 45, extending lengthwise of the car, are supported on the running board saddles and are nailed or otherwise securely fastened thereto. The ridge strips are provided with flanged holes for the bolts 38 and 42 for the running board saddles, the flanges projecting up closely around the bolts to prevent water from following the bolts into the car.

From the foregoing description it is evident that the roof sheets are free to move upon the car substructure in response to distortions thereof, but are positively located in proper position and held from slipping off the eaves by the bosses and saddles. The ridge strips are fixed in position by bolts, and maintain the central alignment of the roof sheets. The ridge and side seam covers permit movement of the roof sheets, and the form of the interlock between them prevents water from entering the car through the seams. The ridge strips catch any water which may get through the ridge caps or between them and the roof sheets, and deflect this water away from the ridge of the car. The amount of water which will reach the ridge strip is small, and there is little chance of its going through the tongued and grooved sheathing boards below the edges of the ridge strip and into the car at any other point than at the ridge.

The invention is not restricted to the precise forms and arrangements of the parts as shown and described.

What I claim as my invention is as follows:

1. A car roof comprising metal roof sheets extending from ridge to eaves, said roof sheets being connected at the ridge by a flexible seam comprising longitudinal cover 130

- strips, a metal strip positioned along the ridge and on each side thereof, said ridge strip being wider than said cover strips and extending under the body portions of the roof sheets beyond the edges of the cover strips and between the ridge ends of the roof sheets continuously from end to end of the car.
2. A car roof comprising metal roof sheets extending from ridge to eaves, said roof sheets being connected at the ridge by a flexible seam, a metal strip fixed in position along the ridge and lapping under the body portions of the roof sheets on each side thereof, said ridge strip being wider than said seam and extending under and between the ridge ends of the roof sheets continuously from end to end of the car and having means engaging said roof sheets for maintaining them in central alinement on the roof.
3. A car roof comprising metal roof sheets extending from ridge to eaves, said roof sheets having pivot recesses at their ridge ends and being connected at the ridge by a flexible seam, a metal strip positioned along the ridge and on each side thereof, said ridge strip being wider than said flexible seam and extending under and between the ridge ends of the roof sheets continuously from end to end of the car and provided with pivots engaging the pivot recesses of said roof sheets.
4. A car roof comprising metal roof sheets extending from ridge to eaves, said
- roof sheets having bosses at their ridge ends and being connected at the ridge by a flexible seam, a metal strip positioned along the ridge and on each side thereof, said ridge strip being wider than said flexible seam and extending under the bosses and between the ridge ends of the roof sheets continuously from end to end of the car, and cross members straddling the ridge and arranged over the bosses of opposite roof sheets to hold them down on said ridge strip, said cross strips and ridge strip being secured to the car at the ridge by means passing between the ridge ends of the roof sheets.
5. A car roof comprising metal roof sheets extending from ridge to eaves, said roof sheets having bosses at their ridge ends and being connected at the ridge by a flexible seam, a metal strip positioned along the ridge and on each side thereof, said ridge strip extending under and between the ridge ends of the roof sheets continuously from end to end of the car and having bosses registering with the bosses of said roof sheets, and cross members straddling the ridge and arranged over the bosses of opposite roof sheets to hold them down on said ridge strip, said cross strips and ridge strip being secured to the car at the ridge by means passing between the ridge ends of the roof sheets.

Signed at Chicago, Illinois, this 8th day of July, 1915.

CLINTON C. MURPHY.
